UNITED STATES PATENT OFFICE.

JAMES W. BONTA, OF PHILADELPHIA, PENNSYLVANIA, ASSIGNOR TO THE AMERICAN NATIONAL TELEPHONE COMPANY, OF NEW YORK.

TELEPHONIC TRANSMITTER.

SPECIFICATION forming part of Letters Patent No. 365,780, dated July 5, 1887.

Application filed December 21, 1886. Serial No. 222,183. (No model.)

To all whom it may concern:

Be it known that I, JAMES W. BONTA, a citizen of the United States, residing at Philadelphia, in the county of Philadelphia and State of Pennsylvania, have invented certain new and useful Improvements in Telephonic Transmitters, of which the following is a specification, reference being had therein to the accompanying drawings, wherein—

10 Figure 1 is a vertical section of a telephonic transmitter embodying my improvements, and Fig. 2 is a section on line 1 1, Fig. 1.

15 My invention has relation to telephonic transmitters, and it has for its object simplicity and economy of construction.

20 My invention consists of the combination, construction, and arrangement of parts, as hereinafter described and claimed, having reference particularly to an electrode having a roller-support and a spring and tension device for varying the contact-pressure between the electrodes.

25 In the drawings, A represents a suitable box or casing, having a removable cap, a, which is provided with a mouth-piece, a', and diaphragm B, which, as shown, may be a plate of carbon hinged to the diaphragm; or it may be fixed or otherwise arranged as desired.

C represents a pencil of carbon or other

suitable material, having, preferably, a rounded 30 front end, c, for contact with the diaphragm B or an electrode thereon. The forward end of electrode C rests upon a grooved or other roller or anti-friction pulley, D, (see Fig. 2,) 35 suitably journaled or supported in casing A. The electrode C is connected at its rear end to a plate or bar spring, E, secured to casing A, and is provided with a tension-screw, e, the 40 tendency of which spring is to move the electrode into contact with the diaphragm. The degree of pressure for such contact is regulated by adjusting screw e.

The electrodes are in the primary 1 of inductorium 2, which primary includes a battery, 3, and the secondary 4 of the inductorium is a part of the line. 45

What I claim is—

In a telephonic transmitter, the combination of diaphragm B and electrode C, having near its front end a supporting-roller, D, and 50 its rear end attached to a spring, E, having tension-screw e, substantially as set forth.

In testimony whereof I affix my signature in presence of two witnesses.

JAMES W. BONTA.
